UNITED STATES PATENT OFFICE.

FREDERICK RENZ, OF BROOKLYN, NEW YORK.

CUTTING MECHANISM.

Original application filed February 16, 1927, Serial No. 168,753. Divided and this application filed November 28, 1927. Serial No. 236,233.

This invention relates to cutting mechanism for use in connection with blank book making machines such as is shown and described in an application filed by me Feb. 5 16, 1927, Serial No. 168,753, blank book making machines, the present application being a division thereof.

A principal object of the invention being to provide accurate, timed automatically 10 controlled mechanism for cutting the usual pre-applied binding tape or strip together with the usual sewing threads connecting the unfinished spaced book units in the passage or feeding movement thereof through the 15 machine to reduce to a minimum the shocks or vibration to the frame of the machine due to such cutting operation.

A further object of the present invention being to obviate some of the objections which 20 are present in patented devices designed for a like purpose.

A primary feature of the construction herein shown and described, is the provision of a horizontally arranged reciprocatory 25 cutter device and means for imparting thereto a rising cross movement relative to the path of travel of the line of temporarily connected work or book units through the machine to sever the connecting tape and 30 sewing threads at the proper time with little or no attending vibration to the frame structure.

The invention possesses other advantageous features which will be set forth in 35 the following detailed description.

The arrangement of the parts may be varied considerably but the present embodiment illustrates the invention now thought to be the best form, but it will be understood 40 that many refinements may be made in the commercial application of the mechanism provided for the purpose set forth.

I clearly illustrate my invention in the accompanying drawings which form a part of 45 this specification, and in which similar reference characters are employed to designate corresponding parts throughout the several views, in which:—

Fig. 1 is a cross sectional elevation of the 50 book making machine shown and described in the parent application above identified and showing the normal relative positions of the cutter mechanism parts with respect

to the pre-taped and sewed book units in their travel through the machine. 55

Fig. 2 is a partial horizontal sectional plan view about on the line 2—2 of Fig. 1.

Fig. 3 is a perspective view of parts of the cutter controlling mechanism.

Fig. 4 is a partial horizontal plan sectional view taken about on the line 4—4 of Fig. 1.

Fig. 5 is a partial sectional side elevation about on the line 5—5 of Fig. 1.

Fig. 6 is a detail side view of the cutter and its operating element.

To clearly illustrate my present invention, I have shown in Fig. 1 of the drawings, a framework 10 such as is employed to support certain parts in the parent application above identified. This framework is preferably formed of side posts 11 and a connecting cross bar 12 from which parallel bearings 13 are suspended to support a part 14 of the book unit feeding mechanism. The 75 other co-acting part 15 of the said feeding mechanism may be mounted on a cross shaft 16 which may be driven from a suitable source of power, preferably by the means employed in the co-pending application 80 above mentioned.

Extending between and supported by the main rails 17 of the machine is a bar, table or platform 18 on which parts of the cutting mechanism are mounted, which mechanism 85 may be described as follows:

A cutter 19 is pivotally connected at one end to an operating disk 20, its other or free end being forked, providing a slot 21 in which a fixed pin 22 is received. The slot 90 extends inwardly from the end of the cutter in a straight longitudinal line as at 23, and then upwardly and inwardly as at 24 to form a cam portion which co-acts with the fixed pin 22 to lift or raise the free end of the cutter as it is drawn across the line of travel of the tape connected book units when severing the said tape connection between the said units at the proper time in their travel through the machine. 95

The above mentioned severing or cutting operation must be accurately timed and quickly executed as the connected book units are moved rapidly through the machine.

I accomplish the above results automatically by employing a novel tripping mech-

anism, controlled by contact with the passing book units and a single revolution clutch controlled by the said tripping mechanism which I will now proceed to describe.

5 A bracket 25 is bolted to an extension of the cross bar 12 of the frame 10, and is formed with an inwardly directed arm 26, a depending arm 27, and side extensions 28 and 29. The end of the arm 26 is formed 10 with a vertical bearing 30 to receive a shaft 31 carrying a feeler or finger 32, and attached to the shaft 31 at its top and above the arm 26 is a lever arm 33 whose hub rests on the said arm 26.

15 The feeler finger 32 keyed to the shaft 31 extends through an opening 34 in a sheet metal side guide 35 as shown in Fig. 4 of the drawings, and urged against one side of the book units as they move by through 20 the instrumentality of a pull spring 36 connected at one end to the lever arm 33 and anchored to the guide 35 at its other end as shown in Fig. 2 of the drawings.

Under the pull of the said spring 36 the 25 feeler finger 32 will ride off the rear ends of the passing book units and will snap inwardly against a properly positioned stop and guide plate 37 mounted on the lower end of a vertical shaft 38 supported at the 30 top from the cross bar 12 of the frame 10.

The above mentioned movement of the finger 32 caused by the pull of the spring 36 partially turns the shaft 31 thus causing the lever arm 33 to draw a connected link 39 35 with it. This link is loosely connected to a hook portion 40 of a rockable tripper 41 which is thus tilted upward on its pivot 42, that is, the free end thereof is raised, and since said free end or nose 43 normally lies 40 under the free end of a trip arm 44 it will raise it a short distance on its pivot pin 45 and release a clutch controlling the movement of the cutter 19 and cause it to sever the before described binding strip as will 45 later appear.

The trip arm 44 is made in two parts connected by an elbow joint 46 which breaks outwardly, the parts being held in alignment by a leaf spring 47.

50 In the automatic operation of quickly resetting the parts of the tripping mechanism, the next oncoming book unit of the line, strikes and forces out the finger 32 from its inward tripped position, which movement 55 partially turns the shaft 31 in the opposite direction, or to the right when viewed from above, and forces the lever arm 33 also to the right, thus pushing the link 39 also in that direction and forcing the nose 43 of the rockable tripper to slightly break the elbow joint of the trip arm 44 permitting said nose to move down under said trip arm to its normal position as best shown in Fig. 3 of the drawings.

65 Briefly, the free end of the trip arm 44

normally lies in the swinging path of the rockable tripper 41 which forces it outwardly in its downward re-setting movement, but said free end snaps back over the nose of the rockable tripper when the parts are in 70 the re-set position and, of course, at the passing of another book unit, the above operations are repeated.

In carrying out my invention, I provide 75 the trip arm 44 with a shoulder 48 against which the free end or nose of a shift lever 49 is urged by a pull spring 50 which is attached at one end to a tail piece 51 of the said lever and at its other end to the extension 29 of the bracket 25.

The shift lever 49 is pivoted as at 52 to the depending arm 27 of the bracket 25 and has pivotal connection with one end of a shift link 53, which is adjustably connected at its other end, as at 54, to an upright oscillatory lever 55 which is pivoted to a fixed standard 56 and has its lower end pin connected to a slide bar 57 operating in guides 58.

The slide bar 57 is turned up at its free 90 end to provide a bearing for a roller 59 and the slide bar also carries a vertical stop pin 60 which normally underlies a projecting pin 61 on a cam sleeve part 62 of a cutter controlling clutch C.

The single revolution clutch C is of well known construction, being shown and described in detail in my above referred to co-pending application, and also in a patent granted to Joseph P. Renz, Feb. 1, 1921, No. 1,366,938, "counter and stacker for sheet material" and is operated when the stop pin 60 is withdrawn from under the projecting pin 61 by a constantly driven sprocket carrying sleeve 63 to impart a full rotation to its 105 shaft 64, and, through gears 65, the disk 20 to which the cutter 19 is pivotally attached.

The slide bar 57 may have a spring connection 66 to normally draw it toward the clutch to maintain the pins 60, 61 in locked 110 engagement to prevent the clutch from turning.

What I claim is:—

1. In a machine for feeding a continuous line of tape connected spaced books, means controlled by the movement of said books for severing the said tape connection between them, consisting of a normally horizontal knife having a tail slot, a pin entering said slot to support and guide the rear end of the knife and mechanism for operating said knife across the path of the said books and between the same.

2. In a machine for feeding a continuous line of spaced tape connected books, the combination with a rotary single revolution clutch, of a horizontally arranged knife having a cam slot in the rear end thereof, a pin entering said slot, said knife having pivotal connection with a part driven by said 130

clutch and mechanism controlled by the passing books for releasing the clutch to draw the knife across the line of movement of the line of books for the purpose described.

3. In a machine for feeding a continuous line of spaced tape connected books, the combination with a rotary single turn clutch, a rotary member geared to said clutch, a knife

10 pivoted to said member and having a cam slot at its free end, a fixed pin entering said slot, a feeler finger adapted to bear on the passing books, a shaft to support said finger and connections for releasing said clutch to

15 operate the knife as each book passes.

4. In a machine for feeding a continuous line of spaced tape connected books, the combination with a single turn clutch, of a rotary member geared thereto, a knife pivotally connected to said member and having a cam slot at its free end, a fixed pin entering said slot, a shaft, a finger on one end of said shaft and a lever arm on the other, means attached to said lever arm for urging 20

25 said finger into yielding contact with the passing books, and connections for releasing said clutch to operate the knife as each book passes.

5. In a machine for feeding a continuous line of spaced tape connected books, the combination with a single turn clutch, of a rotary member geared thereto, a reciprocatory cutter connected to said member, said cutter being provided with an angular slot at its

free end, a fixed pin engaging said slot to 35 support and raise said end in the cutting operation, a vertically arranged rock shaft, a feeler finger and a lever arm on said shaft, a stop and guide plate arranged back of said finger to limit its movement and mechanism 40 connected to said lever arm for releasing the clutch to operate the cutter as each book passes.

6. In a machine for feeding a continuous line of spaced tape connected books, the combination with a single turn clutch, of a rotary member driven thereby, a cutter pivoted to said member and having a cam slot at its free end, means engaging said slot for supporting and raising said end in the cutting 45 operation, a shaft, a feeler finger and a lever arm thereon, an anchored spring having its free end connected to said lever arm, a rockable tripper having a hook and a nose, a link pivoted to the lever arm and engaging said hook, a two part pivoted trip arm normally above the nose of said tripper, said trip arm having a stop shoulder, a spring urged shift lever normally engaging said shoulder, a slide bar having a pin to engage a pin on 50

55 said clutch, and connections between the shift lever and the slide bar for disengaging said pins to release the clutch and operate the cutter as each book passes.

In testimony whereof, I have signed my 60 name to this specification this 14th day of November, 1927.

FREDERICK RENZ.
